UNITED STATES PATENT OFFICE.

JAN MALINIAK, OF PERTH AMBOY, NEW JERSEY.

CAR-STARTER.

1,203,889.

Specification of Letters Patent.

Patented Nov. 7, 1916.

Application filed August 22, 1916. Serial No. 116,220.

To all whom it may concern:

Be it known that I, JAN MALINIAK, a subject of the Emperor of Austria-Hungary, and a resident of Perth Amboy, in the county of Middlesex and State of New Jersey, have invented certain new and useful Improvements in Car-Starters, of which the following is a specification.

This invention relates to improvements in means for moving a car along a railway track and particularly of the type adapted to be manually operated.

The principal object of the invention is to provide means whereby the power is applied directly to the wheel through a lever fulcrumed closely adjacent to its point and adapted to be operated by the weight of the person using the same.

Another object of the invention is to provide means whereby the implement may be rapidly and easily projected forward as the car is advanced and finally to provide such an implement in a form cheap to construct, the parts being strong and durable and particularly well adapted to perform their functions.

These and other objects of like character are attained by the novel construction and combination of parts hereafter described and shown in the accompanying drawing, forming a material part of this disclosure and in which:—

Figure 1 is a perspective view showing the implement positioned upon a track rail. Fig. 2 is a side elevational view, partially in section, of the same and indicating the application of the implement, and Fig. 3 is a transverse sectional view taken on line 3—3 of Fig. 2.

In the drawing the rail, indicated by the numeral 10, consists of a flange, stem and head of the usual cross-section, the car wheel, indicated by the numeral 11, being such as is employed upon the trucks of the car.

The implement is comprised of a sectional base plate, the front section 14 of which has a pair of integrally formed, downward extending lugs 15 adapted to make contact with the head of the rail so that the implement is prevented from slipping off sideways. At the front of the plate other lugs 16 are provided the same rising vertically above the rail and provided with a pivot pin 17 forming a fulcrum for the lever 18, the front or operative end of which is formed with a plurality of sharply indicated corrugations

20 adapted to engage with the periphery of the wheel in such manner that slipping does not readily occur. The opposite outer end of the lever 18 is provided with a pad 21 upon which the foot of the operator may be placed so that his entire weight may be received upon the lever and, as the fulcrum 17 is closely adjacent to the part which makes contact with the wheel, the weight is multiplied and applied with unusual directness to secure the results desired.

Attached rigidly to the base portion 14 is a rear plate 22 having lugs 23 at its outer end in which is a transverse pivot 24 carrying a roller 25 resting upon the head of the rail so as to be easily moved therealong. Disposed between the plate 22 and the lever 18 is a U shaped spring 26 secured to the base element by rivets or otherwise and acting to maintain the lever 18 in a normally raised position so that the point 20 is directed downward where it will engage with the periphery of the wheel. Also rigidly attached to the base plate 22 is a bifurcated post 28, the sides being brought together in the stem extension 29 at the top of which is secured a double handle element 30, adapted to be grasped by the operator's hands whereby he may be steadied in operating the implement, one or both feet being upon the same.

In operation the implement is placed lengthwise upon the track rail so that the lugs 15 rest upon the sides of the rail, and the roller 25 disposed upon the head of the rail, whereupon the implement is pushed forward by means of the handle until the corrugated end 20 makes contact with the wheel; by stepping upon the pad 21 the lever is depressed at that end raising the other end up and making contact with the wheel to cause the same to advance. The operator will then step off the implement and push it forward by means of the handle 30 until a new grip is obtained, whereupon the procedure is repeated.

Having thus described my invention, what I claim as new and desire to secure by Letters Patent, is:—

1. In a car mover, the combination with a base-plate suited to rest upon a rail, means for holding said plate in lateral engagement thereon, a lever fulcrumed on said plate, corrugations formed at the front of said lever adapted to engage with a car wheel, a spring interposed between said base-plate and said lever whereby the latter is held normally

- raised, and means whereby the implement may be propelled along said rail, said means also acting to steady the operator.
2. In a car mover, the combination with a base-plate embracing the head of a rail, vertical lugs formed at the front of said base-plate, a lever pivoted between said lugs, corrugations formed with the front end of said lever, a pad adapted to receive the foot of an operator formed with the rear of said lever, a bifurcated guiding means receptive of the lever, a spring disposed between said base-plate and said lever whereby the latter is held in a normally operative position and a roller mounted at the rear of said base-plate, adapted to rest upon the rail.

3. In a car mover, the combination with a sectional base-plate, lugs in the front section of the same adapted to engage with the side of a rail, a roller carried by the second element of said sectional base-plate, vertical lugs provided with the first named section, a lever pivoted therein, corrugations formed with said lever, a foot pad formed at the opposite end of said lever, a guide secured to the second section of said base-plate and means formed with said guide whereby said implement can be propelled.

Signed at New York, in the county of New York, and State of New York, this 15th day of Aug., 1916.

JAN MALINIAK.

Copies of this patent may be obtained for five cents each, by addressing the "Commissioner of Patents, Washington, D. C."
